UNITED STATES PATENT OFFICE.

ROBERT G. CLARK, OF BROOKLYN, NEW YORK.

APPARATUS FOR PACKING GROUND OR COMMINUTED MATERIAL.

1,275,661.

Specification of Letters Patent.

Patented Aug. 13, 1918.

Application filed September 27, 1916. Serial No. 122,341.

To all whom it may concern:

Be it known that I, ROBERT G. CLARK, a citizen of the United States, residing in the borough of Brooklyn, county of Kings, city and State of New York, have invented new and useful Apparatus for Packing Ground or Comminuted Material, of which the following is a specification.

This invention relates to apparatus for packing ground or comminuted material, such as cork, mixed with a suitable binder into sticks, commonly termed "cork sticks."

To provide a packing for caps for the closure of receptacles, such as bottles, the cap has a composite lining consisting of a thin layer of ground cork and a suitable binder. In the production of this lining the ground cork with the binder is packed and compressed into cylindrical form in a tube and after being packed in the tube is baked to retain the cork with the binder in a compact or compressed and rigid though yielding mass, preferably in elongated cylindrical form, after which disks of predetermined thickness are sliced from the cylinder or stick.

It is the object of the present invention to provide an apparatus to pack the ground cork with the binder into cylindrical form, and to provide an apparatus to simultaneously pack a series of sticks.

In carrying out the invention, an embodiment of which is shown in the accompanying drawings, I provide a hopper having a plurality of outlets and with which outlets a series of pockets are adapted to communicate to receive a predetermined quantity of material from the hopper, together with a carrier for a series of open end tubes having means to serve as an abutment for one end of the tubes, and a series of plungers to eject the material from the pockets into the tubes and compress it therein. The pockets are intermittently rotatable to successively place the pockets in line with the hopper outlets and the plungers so that alternate pockets are in line with said hopper outlets and said plungers. The tube carrier with the tubes is also intermittently rotatable simultaneously with the movement of the pockets to place successive tubes in line with the pockets in line with the plungers.

In the drawings accompanying and forming a part of this specification, Figure 1 is

a perspective view, with parts broken away, 55 of an apparatus showing an embodiment of my invention, and showing the driving means in position to impart movement to the pockets and the tube carrier.

Fig. 2 is a sectional plan view taken on 60 the line 2—2 of Fig. 1 with part of the driving mechanism broken away.

Fig. 3 is a fragmentary sectional view taken substantially on the line 3—3 of Fig. 2 showing the mechanism in position with 65 the plungers compressing material in the tubes.

Fig. 4 is a diagrammatic sectional view of the plungers to illustrate the manner of compressing the material in the tubes. 70

Fig. 5 is a sectional side elevation taken on the line 5—5 of Fig. 2 with part of the driving mechanism broken away; and

Fig. 6 is a perspective view of the stick as produced by the apparatus. 75

Similar characters of reference designate like parts throughout the different views of the drawings.

The embodiment of my invention shown in the drawings consists of a base 7 upon 80 which the operative mechanism is mounted, said base having a vertical column or post 8. Fixed to said base concentric with the column 8 is a support 9 for a series of tubes and which support also serves as an abutment for the tubes. The support has an annular guideway 11 in which the lower end 85 of the tubes engage, the terminals of said guideway being inclined or beveled, as shown at 12, and being adjacent a mouth 13 90 of the support to permit of the ready insertion of the tubes into the guideway.

Rotatably mounted on the column 8 is a turret comprising a sleeve 14 having spaced apart disks 15 fixed thereto, said disks having recesses 16 in the periphery thereof to embrace the tubes adjacent opposite ends and maintain the tubes in spaced apart relation, the tubes being removably retained in said recesses by yielding or springy fingers 16'. 100 Fixed to the sleeve 14 above the upper disk 15 is a head 17 having teeth on the periphery, as shown, and having a series of circumferentially disposed perforations 18, one for each tube, in line with the disk recesses 16, 105 and said perforations having a portion of enlarged diameter or countersunk on the under face of the head, as shown at 19, of

substantially the same diameter as the tubes into which the upper end of the tubes engage, the tubes as they are inserted into the carrier disks 15 through the mouth 13 of the support 9 and are carried up the inclined portions 12 of the guideway 11 are forced into and maintained in engagement in said countersunk portions of the perforations, the diameter of the perforations preferably 10 being slightly less than the internal diameter of the tubes to form a shoulder for the engagement of the material in the tubes when compressed to form an abutment to prevent the material coming out of the top 15 of the tubes due to any expansion force of the material in the tubes when filled.

A head 20 is rotatably supported upon the column 8 above and in juxtaposed relation to the head 17, said head having gear teeth 20 on the periphery and a series of circumferentially disposed openings 21, the number of these openings being twice the number of the perforations 18 in the head 17. The openings 21 are in the nature of measuring 25 devices or pockets, the upper ends of the openings serving as inlets to and the lower ends as outlets from the pockets. These pockets are adapted to receive a predetermined quantity of material from a hopper 30 per H and are adapted to register with outlets 22 of the hopper. The hopper is of annular form the outer walls of which incline inwardly and toward the bottom and the inner wall is of sinuous or concavo-convex form, with the outlets in the concaved portion of said wall within the hopper. The hopper is fixed to a support 23 fixed to the upper end of the column 8 above the head 20, said support having circumferentially 35 disposed openings to register with the hopper outlets, and a second series of circumferentially disposed openings in upwardly extending bosses 24 alternate with the openings in line with the hopper outlets and engaging in the concaved portions of the inner wall of the hopper and outside the latter, as clearly shown in Figs. 1, 2 and 5.

The material from the hopper is fed through the hopper outlets into the measuring 40 pockets 21 and is ejected from the latter into the tubes and compressed in the latter by a series of plungers 25 slidably engaging in the bosses 24. These plungers are slidably supported in a carrier or head 26 fixed to a column 27 having rack teeth 27' which slidably engages in the frame column 8. The plunger carrier is reciprocated by a reciprocable rack 28 pivotally connected at one end, as at 29, to a gear 30 eccentric to 45 the axis of rotation of said gear, the latter being driven from a continuously rotatable shaft 31 through a pinion 32. The upper end of the rack 28 slidably engages in a bracket 33 pivotally supported upon the 50 framework and meshes with a pinion 34

fixed to one end of a shaft 35, a gear 36 also fixed to said shaft meshing with the rack teeth 27' on the column 27.

The composite material, that is, the ground cork and binder, is loose in the 70 hopper and in such condition is fed into the measuring pockets and from the latter into the tubes where it is compressed to substantially one quarter of its volume in the measuring pockets. To feed a quantity 75 of material sufficient to compress and fill the tubes at a single operation is impracticable and for this purpose a predetermined quantity of the material is fed to the tubes and compressed successively in the tubes. 80 Furthermore, to compress material in all of the tubes at the same time to the full capacity of the tubes would require so much power as to make the apparatus impracticable for commercial purposes. For this 85 reason the successive plungers have variable reduced portions, as at 37, and where they engage in the carrier or head 26, (see Fig. 4), the plungers being supported in their uppermost position by the head by collars 90 38 fixed to the ends of the plungers projecting through the head. As the plunger carrier is moved downward the plungers will drop or move with the carrier by gravity and during which movement the material 95 is ejected from the measuring pockets into the tubes, and the plungers are then successively engaged by the head 26 where the shoulder is formed by the reduced portions of the plungers and forced into the tubes 100 compressing the material therein. By varying the lengths of the reduced portions of the plungers the plungers are successively engaged by the carrier or 26, whereby the first plunger, as shown at the extreme right 105 in Fig. 4, compresses the material at the bottom of the first tube in the series, and the succeeding plungers compress successive layers with the last plunger of the series, shown at the extreme left of Fig. 4, compressing the material adjacent the top of 110 the last tube of the series.

To feed and compress successive portions or layers of material in the tubes, the measuring pockets and the tubes are intermittently rotated or advanced. By the intermittent movement of the pockets the pockets are brought successively in place or register with the hopper outlets and the plungers, so that alternate pockets will be 115 120 in register with the hopper outlets and plungers to successively fill and eject the material from the pockets; that is, as material is supplied to certain of the pockets the plungers will be ejecting the material 125 from the pockets alternate with the pockets being filled. Simultaneously with the movement of the measuring pockets the tube carrier with the tubes is rotated or advanced to bring the upper ends of successive tubes 130

in alignment with successive plungers and in register with the outlets of alternate measuring devices. It will thus be seen that the movement of the tube carrier is 5 twice that of the measuring devices.

The intermittent movement is imparted to the tube carrier and the measuring devices or pockets from the continuously rotating shaft 31 by a Geneva gear, comprising a star wheel 39 fixed to a shaft 40, said wheel having curved portions 41 between the projections of the wheel and transverse guideways 42 at right angles and intersecting each other. A pawl or arm 43 is mounted on the shaft 31 to rotate therewith and carries a wheel 44 at one side thereof to operate in the guideways of the star wheel. It will be obvious that as the arm 43 rotates with the shaft 31 the wheel 44 will engage 10 in one end of one guideway and impart a one-quarter turn to the star wheel and will move out of the guideway at substantially right angles to the entrance thereof into the guideway, which movement is transmitted 15 by a bevel gear 45 on a shaft 40 through a bevel gear 46 fixed to a vertical shaft 47, and the movement of the latter shaft is transmitted to the tube carrier by a gear 48 meshing with the gear teeth of the head of the 20 tube carrier or turret, and the movement of the shaft 47 transmitted to the pocket head 25 by a pinion 49 meshing with the gear teeth on said pocket head. To lock the shaft 47 and thereby the pocket head and tube 30 carrier against movement during the periods of rest, a disk 50 on the shaft 31 engages with the curved portions 41 of the star 35 wheel, and as movement is imparted to said star wheel by the arm 43 the projections of 40 the star wheel will engage and pass through a recess 51 in said disk 50.

It will be obvious that the tube carrier and pocket head are moved during the period that the plungers are out of engagement with the pockets, and that the plungers are actuated during the periods of rest of said tube carrier and pocket head, and the actuation of the tube carrier and pocket head are so timed that the movement thereof will 45 take place as the plungers approach their uppermost position. The arm 43 is mounted on the shaft 31 to have axial movement thereon whereby the arm may be thrown into and out of operative engagement with the 50 guideways in the star wheel to impart movement to the latter at a predetermined time with relation to the operation of the plungers. For this purpose the arm is carried by a grooved collar 52 in which the bifurcated end of the shifter arm 53, pivotally supported at 54, engages a spring 55 normally maintaining the shifter and thereby the arm 43 in position so that the roller 44 will not engage in the star wheel guideways. 55 To throw the arm 43 in position so that the

arm will coöperate with the star wheel to impart movement to the latter the gear 30 has a cam 56 at one side to engage with a cam engaging roller 57 carried by the shifter 53.

70

As shown in Fig. 1 the plungers are in their uppermost position and movement is being imparted to the tube carrier and pocket head. Just previous to imparting movement to the tube carrier a tube is inserted into the disk recesses 16 through the mouth 13 of the support 9 and as the turret is rotated the lower end of the tube will run up the incline at the left of the mouth 13 forcing the upper end of the tube into the countersunk portion 19 of the head perforations 18. During the movement of the turret the last and filled tube of the series will ride down the incline at the left of the mouth 13 and may be readily removed or ejected 85 into a receptacle or receiving bin for the same.

75

To assure the ready flow of the material from the hopper into the measuring pockets agitators 59 are provided to agitate the material in the hopper adjacent the hopper outlets, said agitators being rotatably supported to engage in the hopper adjacent the hopper outlets, and are rotated by a sinuous rod 61 connected to each agitator, the said 90 rods engaging in slots in projections 60 on the plunger head 26. As the plunger carrier is moved downward the sinuous rods passing through said slots will rotate the agitators in one direction, and as the carrier 100 moves upward the agitators are rotated in a reverse direction.

90

The apparatus may be driven in a suitable manner, and as shown herein is adapted to be driven by a belt to pass around a pulley 105 58 fixed to the shaft 31.

The material in the tubes as stated is compressed in successive layers in the tubes and after the material has been compressed there is a tendency for such material to expand, 110 and for the purpose of maintaining the compressed material under pressure for the longest time possible during the operation of the plungers is a further object of providing the successive plungers with variable reduced portions. It will be noted from Fig. 4 that as the plunger which compresses the material in the bottom of the tubes is picked up by the plunger carrier to withdraw it from the tubes the remaining plungers still 115 engage in the successive tubes and remain therein until they are successively picked up by the plunger carrier, the weight of the plungers upon the material in the tubes maintaining the compressed material under 120 pressure.

Having thus described my invention, I claim:

1. An apparatus of the class specified, comprising a support for a tube, a hopper, a 130

- measuring device to receive material from the hopper, means to intermittently place said measuring device in register with the outlet of the hopper and the tube, and means 5 to eject the material from the measuring device into the tube and compress it therein, substantially as and for the purpose specified.
2. An apparatus of the class specified, 10 comprising a support for a series of tubes, a hopper having a plurality of outlets, a series of pockets to receive material from the hopper, means to successively place said pockets in register with the hopper outlets and the tubes, and a plunger to eject the material 15 from the pockets into the tubes and compress it therein, substantially as and for the purpose specified.
3. An apparatus of the class specified, 20 comprising means to support a series of tubes in spaced apart relation, a hopper having a plurality of outlets, a series of pockets to receive material from the hopper adapted to be intermittently placed in register with the outlets of the hopper and the tubes, and a series of plungers to eject the material 25 from the pockets into the tubes and compress it therein, substantially as and for the purpose specified.
- 30 4. An apparatus of the class specified, comprising a support for a series of tubes in spaced apart relation; a hopper having a plurality of outlets, a series of pockets to receive material from the hopper, means to alternately place said pockets in register with the hopper outlets and the tubes, plungers to eject the material from the 35 pockets into the tubes and compress it therein, and means to intermittently advance the tubes, substantially as and for the purpose specified.
5. An apparatus of the class specified, 40 comprising a support for a series of open ended tubes; a hopper having a plurality of outlets; a plurality of pockets to receive material from the hopper; means to intermittently move said pockets to alternately place the pockets in register with a hopper outlet and the open end of a 45 tube; means to intermittently move the tube support with the tubes to register with alternate pockets; and plungers to eject the material from the pockets into the tubes, substantially as and for the purpose specified.
- 50 6. An apparatus of the class specified, 55 comprising a support for a series of open ended tubes; a hopper having a plurality of outlets; a plurality of pockets to receive material from the hopper; a plurality of plungers; means to intermittently move the pockets to cause the successive pockets to aline with the plungers and alternate pockets to register with the tubes, substantially as and for the purpose specified.
- 60 65 7. An apparatus of the class specified,
- comprising a support for a series of open end tubes; a hopper having a plurality of outlets; a plurality of pockets to receive material from the hopper; a plurality of plungers; means to intermittently move the pockets to successively aline with the plungers; and means to intermittently move the tube carrier with the tubes to cause successive tubes to aline with successive plungers and to register with the pockets, substantially as and for the purpose specified. 70
8. An apparatus of the class specified, comprising a support for a series of open end tubes; a hopper having a plurality of outlets; a plurality of plungers; a plurality of pockets having inlets and outlets; means to intermittently move the pockets to place the inlets thereof successively in register with the hopper outlets and in alinement with the plungers; and means to intermittently move the tube support with the tubes to place successive tubes in alinement with successive plungers and successive tubes in register with the outlets of alternate pockets, substantially as and for the purpose specified. 75
9. An apparatus of the class specified, comprising a support for a plurality of open end tubes; a hopper having a plurality of outlets; a series of plungers; a plurality of pockets having inlets and outlets to receive material from the hopper; means to intermittently move the pockets to cause successive pockets to alternately aline with the hopper outlets and plungers; and means to support the plungers operable to force the plungers into the tubes to compress the material therein and permit the plungers to rest by gravity upon the compressed material in the tubes, substantially as and for the purpose specified. 80
10. An apparatus of the class specified, comprising a rotatable turret to carry a series of open end tubes in spaced apart relation; a series of plungers; a hopper having a plurality of outlets; a rotatable head having a series of pockets having inlets and outlets to receive material from the hopper; and means to intermittently rotate the turret and pocket head to cause the inlets of successive pockets to register alternately with the hopper outlets and plungers and successive tubes to register with successive plungers and the outlets of alternate pockets, substantially as and for the purpose specified. 85
11. An apparatus of the class specified, comprising a rotatable turret to carry a series of open end tubes in spaced apart relation; a hopper having a plurality of outlets; a rotatable head having a series of pockets with inlets and outlets to receive material from the hopper; means to intermittently rotate the turret and pocket head to cause the inlets of successive pockets to 90
- 100
- 110
- 115
- 120
- 125
- 130

- alternately register with the hopper outlets and to cause successive tubes to register with the outlets of alternate pockets and with pockets which are alternate to the pockets 5 with the inlets in register with the hopper outlets; and means to force the material from the pockets and compress it in the tubes, substantially as and for the purpose specified.
12. An apparatus of the class specified, comprising a turret to carry a series of open end tubes in spaced apart relation; a hopper having a plurality of outlets; a rotatable head having a series of pockets with inlets 15 and outlets to receive material from the hopper; means to intermittently rotate the turret and pocket head to cause the inlets of the successive pockets to alternately register with the hopper outlets and to cause successive tubes to register with the outlets of alternate pockets; a series of plungers, one for each tube; and means to support said plungers in line with the tubes and with alternate pockets, said support being operable to force the plungers into the tubes to compress the material therein and to permit the plungers to rest by gravity on the material in the tubes, substantially as and for the purpose specified.
13. An apparatus of the class specified, comprising a rotatable turret to carry a series of open end tubes in spaced apart relation; a hopper having a plurality of outlets; a rotatable head having a series of 35 pockets with inlets and outlets to receive material from the hopper; means to intermittently rotate the turret and pocket head to cause the inlets of successive pockets to alternately register with the hopper outlets and to cause successive tubes to register with the outlets of alternate pockets; a series of plungers, one for each tube; a carrier to support the plungers in alinement with alternate pockets and successive tubes; and means 40 to actuate said carrier to cause the plungers to eject the material from the pockets into the tubes and compress the material in the latter, substantially as and for the purpose specified.
14. An apparatus of the class specified, comprising a rotatable turret to carry a series of spaced apart tubes; a hopper having a plurality of outlets; a rotatable head having a series of pockets with inlets and outlets to receive material from the hopper; means to intermittently rotate the turret and pocket head to cause the inlets of successive pockets to alternately register with the hopper outlets and to cause successive tubes to 55 register with the outlets of alternate pockets and with pockets which are alternate to the pockets with the inlets in register with the hopper outlets; a series of plungers, one for each tube; a carrier for said plungers comprising a head in which the plungers are slidably carried; and means to reciprocate the head during the periods of rest of the turret and pocket head, substantially as and for the purpose specified.
15. An apparatus of the class specified 70 comprising a rotatable turret to carry a series of tubes in spaced apart relation; a hopper having a plurality of outlets; a rotatable head having a series of pockets with inlets and outlets to receive material from the hopper; means to intermittently rotate the turret and pocket head to cause the inlets of successive pockets to alternately register with the hopper outlets and to cause successive tubes to register with the outlets of alternate pockets and with pockets which are alternate to the pockets with the inlets in register with the hopper outlets; a series of plungers, one for each tube; a head in which the plungers are slidably carried; and means 75 to reciprocate the head comprising a reciprocable rack, a shaft, a gear on the shaft to mesh with the rack, a slideable support for the head having rack teeth, and a second gear on the shaft meshing with said rack teeth, substantially as and for the purpose specified.
16. In a device of the class specified, the combination of a hopper having a plurality of outlets; plungers; a plurality of pockets 95 to receive material from the hopper outlets, means to successively place the pockets alternately in register with the hopper outlets and plungers, and a support and carrier for a series of spaced apart tubes intermittently 100 operable to place successive tubes in register with alternate pockets in register with the plungers, substantially as and for the purpose specified.
17. In a device of the class specified, the combination of a hopper having a plurality of outlets; plungers; a plurality of pockets to receive material from the hopper outlets; and means to carry a series of open end tubes in spaced relation, comprising a fixed 110 part to support and serve as an abutment for one end of the tubes and having an annular guideway for the tubes, a pair of spaced apart disks having recesses in the periphery to embrace the tubes adjacent 115 opposite ends, and a head rotatable with the disks having perforations for the engagement of the open ends of the tubes, substantially as and for the purpose specified.
18. In a device of the class specified, the combination of a hopper having a plurality of outlets; plungers; a plurality of pockets to receive material from the hopper outlets; means to carry a series of open end tubes in spaced apart relation, comprising a fixed 125 member to support and serve as an abutment for one end of the tubes and having an annular guideway for the tubes, a pair of spaced apart rotatable disks having recesses in the periphery to embrace the tubes adjacent 130

- 8
- opposite ends, a head rotatable with the disks having perforations for the engagement of the open ends of the tubes, and means to intermittently rotate the disks and head with the tubes to successively place the open ends of the tubes in register with alternate pockets, substantially as and for the purpose specified.
19. In a device of the class specified, the combination of a hopper having a plurality of outlets; a rotatable head having gear teeth on the periphery and a plurality of pockets having inlets and outlets to receive material from the hopper; a rotatable carrier for a series of open end tubes including a head supported in juxtaposed relation to the pocket head, said head having gear teeth on the periphery and perforations in which the open ends of the tubes engage; means to intermittently rotate the pocket head to cause the inlets of alternate pockets to successively register with the hopper outlets and to cause the open ends of successive tubes to register with the outlets of the pockets alternate with the pockets having the inlets in register with the hopper outlets, comprising a rotatable shaft, gears on said shaft to mesh with the teeth of the pocket head and the head of the tube carrier, a rotatable shaft, and a Geneva gear to impart movement intermittently from said latter shaft to the first shaft; and plungers to align with the tubes and pockets alternate with the pockets in register with the hopper outlets during the periods of rest to eject the material from the pockets into the tubes and compress it therein, substantially as and for the purpose specified.
20. In a device of the class specified, the combination of a hopper having a plurality of outlets; a rotatable head having gear teeth on the periphery and a plurality of pockets having outlets and inlets to receive material from the hopper; a rotatable carrier for a series of open end tubes including a head supported in juxtapose relation to the pocket head, said head having gear teeth on the periphery and perforations in which the open ends of the tubes engage; a pair of pinions to mesh with the gear teeth of the pocket head and the head of the tube carrier; and means to impart intermittent movement to said pinions and thereby to the tube carrier and pocket head, comprising a star wheel having transversely extending guideways in one face thereof operatively connected to the pinions, a continuously rotating shaft, and a pawl mounted on the shaft to rotate therewith and have sliding movement thereon to engage in the guideways of the star wheel, substantially as and for the purpose specified.
21. In a device of the class specified, the combination of a hopper having a plurality of outlets; a rotatable head having gear teeth on the periphery and a plurality of pockets having outlets and inlets to receive material from the hopper; a rotatable carrier for a series of open end tubes including a head supported in juxtaposed relation to the pocket carrier, said head having gear teeth on the periphery and perforations in which the open ends of the tubes engage; a pair of pinions to mesh with the gear teeth of the pocket head and the head of the tube carrier; and means to impart intermittent movement to said pinions and thereby to the tube carrier and pocket head, comprising a star wheel having transverse guideways in one face thereof and curved portions between the projections, a continuously rotating shaft, a pawl mounted on the shaft to rotate therewith and have sliding movement thereon to engage in the guideways of the star wheel, means to slide said pawl on the shaft to throw the same into and out of operative engagement with the guideways in the star wheel at a predetermined time, and a disk rotatable with the shaft to engage with the curved portions of the star wheel to lock the latter against movement and having a recessed portion for the passage of the projections of the star wheel, substantially as and for the purpose specified.

ROBERT G. CLARK.
